CLAIM

I claim the ornamental design for a head protector, as shown and described.

DESCRIPTION

FIG. 1 is a front view of a head protector showing my new design;

FIG. 2 is a front and right side perspective view thereof;

FIG. 3 is a top view thereof;

FIG. 4 is a rear view thereof;

FIG. 5 is a right side view thereof, with the ear protection raised;

FIG. 6 is a right side view thereof, with the ear protection and face shield raised; and,

FIG. 7 is a right side view thereof, with the face shield raised. Any surfaces of the design not shown, including interior or bottom surfaces, form no part of the claimed invention.
